(57) **CLAIM**

The ornamental design for a keypad for a portable electronic device, as shown and described.

DESCRIPTION

FIG. 1 is a front perspective view of a keypad for a portable electronic device in accordance with our new design;

FIG. 2 is a top view thereof;

FIG. 3 is a front elevational view thereof;

FIG. 4 is bottom plan view thereof; and,

FIG. 5 is a right side elevational view thereof, the left and right sides of the keypad for a portable electronic device being symmetrical to one another;

The rear view forms no part of the design and is omitted. The broken line showing of environmental structures is for illustrative purposes only and forms no part of the claimed design.
